UNITED STATES PATENT OFFICE.

HUGH M. McCORMICK, OF DETROIT, MICHIGAN, ASSIGNOR TO AMERICAN CORSET STAY COMPANY, OF PHOENIX, ARIZONA TERRITORY.

CORSET.

1,006,863.

Specification of Letters Patent. Patented Oct. 24, 1911.

Application filed March 21, 1910. Serial No. 550,734.

To all whom it may concern:

Be it known that I, HUGH MALCOLM McCORMICK, a citizen of the United States, residing at Detroit, in the county of Wayne 5 and State of Michigan, have invented a new and useful Corset, of which the following is a specification.

My invention relates to improvements in devices for abdominal support in combination with a corset, and the object thereof is to provide, first, adequate support for the lower abdomen by means of the abdominal-compressing and supporting portions or members of my invention; second, a waist-belt to restrain and retain the pendulous upper abdomen overhanging the said abdominal-compressing and supporting portions; third, to produce by these means, combined with a corset, a correct and graceful figure. I attain these objects by the means illustrated in the accompanying drawing, in which:

Figure 1 shows the corset provided with the abdominal-compressing and supporting portions and with the waist-belt; Fig. 2 shows the corset provided with said abdominal-compressing and supporting portions and with said waist-belt, on the figure, the abdominal-compressing and supporting portions being shown in operation, and the waist-belt unlaced; Fig. 3 shows the corset on the figure, with both said abdominal-compressing and supporting portions and the waist-belt laced, preparatory to closing and fastening the corset thereover.

The abdominal-compressing and supporting portions or members A obliquely and independently operate directly upon the lower abdomen within a contracting circle (the corset), their function being to provide immovable, intra-pelvic, sub-abdominal support. The abdominal-compressing and supporting portions are carried, preferably, on the under surface of the corset. The waist-belt B, also 45 carried preferably on the under surface of the corset, and formed in two sections, is designed and intended to complement the said abdominal compressing and supporting portions A, by taking care of the pendulous

middle and upper abdomen C, overhanging 50 the portions A, compressing or reducing said pendulous middle and upper abdomen C in such manner that the corset proper D can be closed over both the waist-belt B and the abdominal-compressing and supporting portions A, upon an already elevated and compressed abdomen.

The abdominal-compressing and supporting portions A, as shown in the drawing, depend upon the side and rear of the corset 60 for their base. The waist-belt B is preferably attached, as shown, at or near the vertical side-line of the corset. Both the abdominal-compressing and supporting portions and the waist-belt are provided with 65 eyelets for lacing.

In operation, the corset is put on and hooked at the top by one clasp. The abdominal-compressing and supporting portions A are then adjusted upon the lower 70 abdomen and laced to suit the wearer's need or convenience. The waist-belt (which preferably partly overlaps the top of the abdominal-compressing and supporting portions A) is next laced until the figure is suitably reduced. After this, the remaining clasps of the corset are fastened over both the waist-belt B and the abdominal-compressing and supporting portions A, and the corset D is tightened to please the wearer, in the usual 80 way.

Having thus fully described my invention, what I claim as new and desire to secure by Letters Patent is:

In combination, a corset and abdominal-compressing and supporting portions disposed obliquely on the inner surface thereof and supporting the sub-abdomen of the wearer, and a waist-belt formed in two sections overhanging the abdominal-compressing and supporting portions, and compressing the middle and upper abdomen of the wearer.

HUGH M. McCORMICK.
